Primary Examiner — Michelle E. Wilson*Assistant Examiner* — Richard E Yenchesky(74) *Attorney, Agent, or Firm* — Cantor Colburn LLP(57) **CLAIM**

We claim, the ornamental design for a floor cleaning system, as shown and described.

DESCRIPTION

FIG. 1 is a front perspective view of our design;

FIG. 2 is a rear perspective view of our design;

FIG. 3 is front view of our design;

FIG. 4 is a rear view of our design;

FIG. 5 is a first side view of our design;

FIG. 6 is a second side view of our design;

FIG. 7 is a top view of our design; and,

FIG. 8 is a bottom view of our design.

The broken lines depict portions of the floor cleaning system in which the design is embodied that are not considered part of the claimed design.
